H. O. HOLTE

RAILWAY TRAFFIC CONTROLLING APPARATUS

Filed Dec. 18, 1924

UNITED STATES PATENT OFFICE.

HAROLD O. HOLTE, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed December 18, 1924. Serial No. 756,710.

My invention relates to railway traffic controlling apparatus, and particularly to apparatus of the type comprising train carried governing mechanism controlled by energy received from the trackway.

I will describe one form of apparatus embodying my invention, and will then point out the novel features thereof in claims.

In the accompanying drawing, Fig. 1 is a view, partly diagrammatic and partly in isometric projection, showing one form of apparatus embodying my invention. Fig. 2 is detailed view of a circuit controller J forming part of the apparatus shown in Fig. 1.

Similar reference characters refer to similar parts in each of the views.

Referring first to Fig. 1, the reference characters 1 and 1^a designate the track rails of a railway along which traffic normally moves in the direction indicated by the arrow. These rails are divided by insulated joints 2 to form track sections of which only one section X—Y is shown in the drawing.

This track section X—Y is provided with trackway apparatus for transmitting impulses to trains, which apparatus is designated as a whole by the reference character A. The impulse transmitting apparatus A comprises a source of current, such as a generator 6, constantly driving a motor 7. The motor 7 is operatively connected with three circuit interrupting devices 3, 4 and 5, all of which rotate at the same speed. The circuit interrupting device 3 is provided with two oppositely disposed contact segments 3^a electrically connected by a conductor 3^b and arranged to make electrical contact with a pair of oppositely disposed brushes 62. The circuit interrupting device 4 is provided with four contact segments 4^a, all of which are electrically connected by wires 4^b, and which segments co-act with a pair of oppositely disposed brushes 63. The circuit interrupting device 5 is provided with eight contact segments 5^a, all of which are electrically connected by conductors 5^b, and are arranged to co-act with a pair of oppositely disposed brushes 64. Associated with the circuit interrupting device 3 is a circuit controller 8 which is opened or closed according to traffic conditions in advance of the track section X—Y, and similar circuit controllers 8^a and 8^b, controlled in similar man-

ner, are associated with the circuit interrupting devices 4 and 5, respectively. When circuit controller 8 is closed the generator 6 is connected across the track rails 1 and 1^a through the circuit interrupting device 3, so that two impulses will be impressed across the track rails for each complete revolution of the device 3. When circuit controller 8^a is closed the generator 6 is connected across the rails through the circuit interrupting device 4, whereby four impulses will be impressed across the rails during each complete revolution of the device 4. Similarly when circuit controller 8^b is closed the generator 6 will be connected across the rails through the circuit interrupting device 5, so that eight impulses will be impressed across the rails during each complete revolution of the device 5. Inasmuch as the devices 3, 4 and 5 are driven at the same speed by the motor 7, which motor is constantly in operation, it will be seen that impulses at different frequencies are impressed across the track rails, depending on traffic conditions in advance of the section X—Y. As shown in the drawing, the generator 6 produces alternating current, although current of this characteristic is not essential to my invention. When alternating current is used, it is, of course, apparent that each impulse impressed across the rails is in reality made up of a group of alternating current impulses, but for purposes of this specification I will hereinafter refer to each of these groups as an impulse.

Located in the track section X—Y is train W provided with apparatus for receiving the impulses impressed across the rails by the transmitting apparatus A. As here shown, the receiving apparatus on the train W comprises a pair of receiving coils 9 and 9^a located in front of the forward wheels of the train and disposed in inductive relation with the two track rails 1 and 1^a respectively. These coils 9 and 9^a are connected in a receiving circuit 10 in such manner that the voltages created in the coils by alternating current flowing in the two track rails in series are additive. This receiving circuit 10 controls a primary relay C in such manner that the relay C is energized during each impulse impressed across the track rails and de-energized during the interval between impulses. If desired, an amplifier

11 may be interposed between the receiving circuit and the primary relay C.

The train carried apparatus includes a second relay D provided with a pick-up circuit which is controlled by a back contact of the primary relay C. This pick-up circuit passes from terminal B of a suitable source of current, through back contact 12-12^b of relay C, wires 13 and 14, winding 16 of relay D, and wire 16 to terminal O of the same source of current. It will be seen, therefore, that relay D is energized whenever the primary relay C is de-energized. Relay D is also provided with a stick circuit which passes from terminal B, through contact 17-17^a of a circuit controller N, wire 18, front contact 19 of relay D, wire 14, winding of relay D, and wire 16 to terminal O. Circuit controller N is operated in a manner hereinafter set forth. Contact 17-17^a is normally closed, however, and so it will be noted that when relay D becomes energized it will remain energized after relay C becomes energized and until contact 17-17^a becomes opened.

The train carried apparatus includes a movable member G, which, as here shown, is a shaft pivotally mounted at points 34. This shaft is biased to swing in counter-clockwise direction as viewed in the drawing, that is, in the direction indicated by the arrow a. The shaft is provided with a motor device F for swinging the shaft in clockwise direction in opposition to the biasing force, and also with a retarding device K for retarding the return movement of the shaft under the influence of its biasing force. Fixed to the shaft G is a finger 62 for causing operation of the circuit controller N, and also associated with the shaft G is a circuit controller J.

The motor device F comprises a solenoid 29 and a plunger 30, which plunger is operatively connected through a link 66 with a collar 65 fixed to the shaft G. When the solenoid 29 is energized, it draws the plunger 30 downwardly thereby turning the shaft G in clockwise direction in opposition to the biasing force acting on the shaft.

The retarding device K comprises a vane 33 of electro-conducting non-magnetizable material fixed to the shaft and moving between the pole pieces of a magnetizable core 32 which is provided with a winding 31. When the winding 31 is energized, the magnetic field passing through the vane 33 tends to retard the movement of this vane and so to retard the angular motion of the shaft G. The weight of vane 33 may be the force which biases the shaft G in counter-clockwise direction.

The circuit controller J comprises a member 70 which is mounted loosely on the shaft G, but the downward movement of which, that is, the movement in clockwise direc-

tion, is limited by a stop 38 fixed to the shaft G. This circuit controller member 70 comprises three contact segments 35, 36 and 37, disposed in different planes perpendicular to the shaft G, this arrangement being shown more clearly in Fig. 2. The three segments 35, 36 and 37 are arranged for co-operation with three contact fingers 35^a, 36^a and 37^a, respectively, which contact fingers are carried by an armature 24 of an electro-responsive device E. The device E also comprises a magnet 23 for attracting the armature 24. When the armature 24 is retracted, the contact fingers 35^a, 36^a and 37^a are out of the paths of the contact segments 35, 36 and 37, but when the armature 24 is attracted by the magnet 23, these contact fingers are all in the paths of the corresponding contact segments, so that one contact or another will be closed, depending upon the angular position of the circuit controller member 70.

The circuit controller N is operated in the following manner: When the shaft G occupies its normal or biased position, that is, the position in which it is shown in the drawing, the finger 62 engages contact member 47 so that contact 47-49 is closed and contact 47-48 is open; contact 17-17^a is closed. When the shaft G begins to swing in clockwise direction under the action of motor device F the finger 62 releases member 47 thereby allowing contact 47-49 to open and contact 47-48 to close. When the shaft reaches its extreme clockwise position, which I will term its "initial" position, finger 62 engages member 17 to open contact 17-17^a. During the reverse movement of the shaft in response to its biasing force, contact 17-17^a closes as soon as the shaft leaves its initial position, and as the shaft reaches its normal position contact 47-48 opens and contact 47-49 closes.

The train W is provided with train governing apparatus controlled by the circuit controllers N and J, which apparatus may assume any desired form. It may comprise means for governing the brakes of the train, or it may comprise speed responsive elements for governing the brakes in accordance with speed and traffic conditions, or it may comprise merely signaling devices for indicating traffic conditions to the engineer. In order to make the present disclosure as simple as possible I have shown this train governing apparatus as comprising signaling devices only, these devices being electric lamps H, M, L and S. The lamps L, M and H are controlled by slow releasing relays 41, 44 and 46, respectively, which in turn are controlled by the circuit controller J, whereas the lamp S is controlled by circuit controller N.

In explaining the operation of the apparatus, I will assume that all three circuit controllers 8, 8^a and 8^b have been opened for

a sufficient interval of time to permit all parts of the train carried apparatus to assume the positions to which they are biased, that is, to assume the positions in which they are shown in the drawing. The stop lamp S is then lighted, its circuit being closed through contact 47-49 and wire 50. Lamps L, M and H are all extinguished because relays 41, 44 and 46 are all open. I will next assume that while the train W occupies section X-Y circuit controller 8 becomes closed. Two impulses are then impressed across the track rails 1 and 1' during each revolution of the circuit interrupting device 3, so that the primary relay C is energized twice during each such revolution. When relay C becomes energized, it, of course, opens its back contact and closes its front contact. The opening of the back contact 12-12^b opens the pick-up circuit for relay D, but relay D remains closed due to its stick circuit through circuit controller N. The closing of the front contact 12-12^a of relay C closes a circuit for magnet 23 of the electro-responsive device E, this circuit being from terminal B through front contact 12-12^a of relay C, wire 20, winding of magnet 23, wire 21, contact 22 of relay D, and wires 15 and 16 to terminal O. Magnet 23 then attracts its armature 24, thereby moving the contact fingers 35^a, 36^a and 37^a into the paths of the contact segments 35, 36 and 37. The attraction of armature 24 also closes a contact 25-26 and opens a contact 25-27. Contact 25-26 closes a circuit for motor device F which passes from terminal B, through contact 25-26, wire 28 and solenoid 29 to terminal O. The opening of contact 25-27 de-energizes the retarding device K, so that the shaft G is free to move without retardation. Motor F then functions to swing the shaft G in clockwise direction in opposition to the biasing force acting on this shaft. The retarding device K being de-energized, the rate of movement is limited only by inertia and the resistance offered by the pivots 34, so that this movement of the shaft G takes place in a very brief interval of time.

As soon as this movement of shaft G begins, contact 47-49 of circuit controller N opens, thereby extinguishing the stop lamp S, and contact 47-48 closes. After a slight movement of shaft G has occurred, contact segment 35 engages contact finger 35^a, and this engagement does two things. It stops further movement of circuit controller member 70 so that during subsequent movement of the shaft this member remains at rest and the stop 38 moves away from the member. It also closes a circuit for relay 41 which circuit passes from terminal B through circuit controller member 70, contact 35-35^a, wire 40, and winding of relay 41 to terminal O. This causes the low speed

lamp L to become lighted, the circuit being from terminal B through contact 47-48 of circuit controller N, wire 52, contact 54 of relay 41, wire 57, and lamp L to terminal O. When the shaft G reaches its initial position, contact 17-17^a of circuit controller N opens, thereby opening the stick circuit for relay D which consequently becomes opened, and this in turn de-energizes winding 23 of device E at contact 22 of relay D. Device E then releases its armature 24, so that contact finger 35^a releases the member 70 which immediately swings downwardly until arrested by the stop 38, the member then being in its "initial" position. The release of armature 24 also reverses contact member 25, thereby de-energizing the motor device F and energizing the retarding device K, the circuit for the retarding device being from terminal B through contact 25-27, wire 61, and winding 31 to terminal O. The shaft G and member 70 thereupon begin to swing in counterclockwise direction due to the biasing force acting on the shaft, this movement being retarded, however, by the action of the device K so that the movement or swing takes place in accordance with lapse of time. While the shaft is making this return movement, relay C becomes de-energized due to the opening of contact interrupter 3, and so relay D again becomes energized. When the shaft has made a sufficient angular movement to bring the contact segment 35 into registry with finger 35^a, relay C again becomes energized due to the closure of the transmitting circuit at circuit interrupter 3. Armature 24 is then attracted again, thereby closing contact 35-35^a and so closing the circuit through the slow releasing relay 41, this circuit being from terminal B, through contact 35-35^a, wire 40, and winding of relay 41 to terminal O. Relay 41 then becomes energized, thereby closing a circuit for low speed lamp L, which circuit is from terminal B, through contact 47-48, wire 52, contact 54 of relay 41, wire 57, and lamp L to terminal O. The energization of device E also reverses contact member 25, thereby de-energizing the retarding device K, and energizing the motor device F, so that shaft G is again restored to its initial position. During this restoring movement the contact member 70 is held stationary by the co-action of contact segment 35 with contact finger 35^a, so that the slow releasing relay 41 remains energized during this movement. As soon as the shaft G is fully restored to its initial position, however, circuit controller N is again operated to open relay D, which in turn de-energizes magnet 23, thereby releasing contact member 70, which immediately drops to its lowest position against the stop 38. The return movement of shaft G is then repeated until relay C again becomes energized,

whereupon the device E is again operated to arrest the motion of the shaft G and to energize the slow releasing relay 41. It will be seen, therefore, that as long as impulses are transmitted by the circuit interrupter 3 of the transmitting apparatus A the low speed lamp L will be lighted.

Assuming now that circuit controller 8 becomes opened and circuit controller 8^a becomes closed, it will be noted that the frequency of the impulses transmitted to the track rails will be doubled. Under this condition the movement of shaft G in counter-clockwise direction will be arrested when contact segment 36 registers with contact finger 36^a, so that slow releasing relay 44 will be energized thereby lighting the medium speed lamp M. The circuit for relay 44 is from terminal B, through segment 36, contact finger 36^a, wire 43, winding of relay 44, to terminal O. The circuit for the medium speed lamp M is from terminal B, through contact 47-48, wire 52, contact 55 of relay 44, wire 58 and lamp M to terminal O.

I will now assume that in the trackway apparatus A the circuit controllers 8 and 8^a are both opened and circuit controller 8^b is closed. The frequency of the impulses will again be doubled and the train carried apparatus is so adjusted that each counter-clockwise movement of shaft G will be arrested when contact segment 37 registers with contact finger 37^a. Slow releasing relay 46 will then be energized by a circuit passing from terminal B, through contact 37-37^a, wire 45, winding of relay 46, to terminal O. The high speed lamp H will then be energized, the circuit for this lamp being from terminal O, through contact 47-48, wire 52, contact 56 of relay 46, wire 59, and lamp H to terminal O.

It will be noted that during the repeated transmission of any code to the train, the corresponding slow releasing relay 41, 44 or 46 is de-energized during the time interval between each de-energization of the electro-responsive device E and the next successive energization of this device. Each of these relays is so designed that its contact 54, 55 or 56 will not open during this time interval.

If desired, a small piece of soft iron 60 may be attached to the vane 33 in such position as to approach the pole pieces of the 55 retarding device K just as the shaft G completes its movement in counter-clockwise direction when the code signals cease. The attraction of the core 32 on this piece of iron will assist the action of gravity on the shaft 60 in reversing contact member 47 of circuit controller N.

If the supply of alternating current to the train carried receiving windings 9 and 9^a ceases, the parts of the apparatus will assume the position in which they are shown

in the drawing, so that the stop lamp S will be lighted. If alternating current should be supplied continuously to the track rails, the primary relay C will remain energized, relay D will be opened by the first operation 70 of shaft G and will thereafter remain open because its pick-up circuit is open at back contact 12-12^b of relay C, and so there will be no subsequent operations of the shaft G. This shaft will therefore assume its normal 75 position wherein it is shown in the drawing, so that the stop lamp S will be lighted.

It will be seen that the train carried apparatus is selectively responsive to the time interval from the beginning of each trackway impulse to the beginning of the next succeeding impulse, and that the time interval between impulses is immaterial. That is to say, shaft G is restored to its initial position upon the beginning of each impulse and 80 immediately begins its return movement regardless of the length of the impulse, because the return movement of the shaft is initiated by the opening of circuit controller N, and the opening of this circuit controller is dependent solely upon the shaft G being in its initial position. The timing force is gravity 85 opposed by saturated electro-magnetic damping and the small frictional torque in three pivots. There is a small elastic force acting 95 at each end of the timing stroke, but over the main part of the stroke there is none. There are no parts of the apparatus connected by links whose pivots might wear and allow lost motion. The time element of each 100 contact is permanent and not affected by contact wear. One important feature of the apparatus is that friction and elastic torques, both of which are erratic, are practically 105 eliminated from the forces that affect the timing.

Although I have herein shown and described only one form of apparatus embodying my invention, it is understood that various changes and modifications may be 110 made therein within the scope of the appended claims without departing from the spirit and scope of my invention.

Having thus described my invention, what I claim is:

1. Railway traffic controlling apparatus comprising means in the trackway for supplying impulses to trains, and train carried governing mechanism selectively responsive to the time interval between a given instant 115 in each impulse and the corresponding instant in the next impulse.

2. Railway traffic controlling apparatus comprising means in the trackway for supplying impulses to trains, means controlled 120 by traffic conditions for varying the time interval between the beginning of each impulse and the beginning of the next impulse, and train carried governing mechanism selectively responsive to the time interval between a 125 130

given instant in each impulse and the corresponding instant in the next impulse.

3. Railway traffic controlling apparatus comprising a train carried member biased in one direction, means for retarding the movement of said member in the said one direction but not in the other direction, apparatus located partly on the train and partly in the trackway for moving said member in the said other direction to an initial position at intervals spaced in accordance with traffic conditions, and governing mechanism on the train selectively responsive to the amount of movement made by said member 15 away from such initial position between successive intervals.

4. Railway traffic controlling apparatus comprising a train carried member biased to move away from an initial position, means 20 for retarding the movement of said member away from but not toward its initial position, apparatus located partly on the train and partly in the trackway for restoring said member to its initial position at intervals spaced in accordance with traffic conditions, and governing mechanism on the train selectively responsive to the amount of movement made by said member between successive restorations.

30 5. Railway traffic controlling apparatus comprising means on a train arranged to change from an initial condition toward an ultimate condition in accordance with lapse of time, apparatus located partly on the 35 train and partly in the trackway for restoring said means to its initial position at intervals spaced in accordance with traffic conditions, and governing mechanism on the train selectively responsive to the amount of 40 change accomplished by said train carried means between successive restorations.

6. Railway traffic controlling apparatus comprising means on a train arranged to change from an initial condition toward an 45 ultimate condition in accordance with lapse of time, apparatus located partly on the train and partly in the trackway for restoring said means to its initial position at intervals spaced in accordance with traffic conditions, and mechanism on the train for indicating different speed limits according to the 50 amount of change accomplished by said means between successive restorations.

7. Railway traffic controlling apparatus 55 comprising a train carried member biased to move away from an initial position, means for retarding the movement of said member away from but not toward its initial position, apparatus located partly on the train 60 and partly in the trackway for restoring said member to its initial position at intervals spaced in accordance with traffic conditions, and mechanism on the train for indicating different speed limits according to the

amount of movement made by said member 65 between successive restorations.

8. Railway traffic controlling apparatus comprising means in the trackway for transmitting impulses at different frequencies under different traffic conditions, means on a 70 train arranged to change from an initial condition in accordance with lapse of time, apparatus on the train for restoring said means to its initial condition in response to each impulse from said trackway means, 75 and governing mechanism on the train selectively responsive to the amount of change accomplished by said train carried means between successive restorations.

9. Railway traffic controlling apparatus 80 comprising means in the trackway for transmitting impulses at different frequencies under different traffic conditions, a train carried member biased to move away from an initial position, means for retarding the 85 movement of said member away from but not toward its initial position, apparatus on the train for restoring said member to its initial position in response to each impulse from said trackway means, and governing 90 mechanism on the train selectively responsive to the amount of movement made by said member between successive restorations.

10. Railway traffic controlling apparatus comprising means in the trackway for transmitting impulses at different frequencies under different traffic conditions, a train carried relay energized in response to each impulse from said trackway means, a second train carried relay, a pick-up circuit for said 100 second relay closed when said first relay is de-energized, a train carried member biased to move from an initial position, a stick circuit for said second relay including a front contact thereof and a contact which is 105 open when said member is in initial position but closed in all other positions of the member, a motor for moving said member to its initial position, electric apparatus for retarding movement of said member, a train 110 carried electro-responsive device having a magnet and an armature, a circuit for said device controlled by a front contact of said first magnet and a front contact of said second magnet, means for energizing said motor when said device is energized and for energizing said retarding apparatus when 115 said device is de-energized, a plurality of contact segments associated with said member, a plurality of contact fingers one for each segment and normally out of engagement with the segments but moved into engagement with said segments when the armature is attracted by its magnet, and governing mechanism on the train controlled by 120 said contact elements.

11. Railway traffic controlling apparatus comprising means in the trackway for trans-

mitting impulses at different frequencies under different traffic conditions, a train carried relay energized in response to each impulse from said trackway means, means on 5 the train arranged to change from an initial condition in accordance with lapse of time, apparatus for restoring said means to its initial condition each time said relay becomes energized, and governing mechanism on the 10 train selectively responsive to the amount of change accomplished by said train carried means between successive restorations.

12. Railway traffic controlling apparatus comprising a train carried shaft biased to 15 turn away from an initial position, a retarding device for retarding the movement of said shaft in response to the biasing force, a contact segment mounted to swing on said shaft and biased to turn in the direction 20 opposite to the shaft, a stop fixed to said shaft for limiting the movement of said segment with respect to the shaft, a contact finger normally out of the path of said segment, means located partly on the train 25 and partly in the trackway for periodically moving said contact finger into the path of said segment and simultaneously restoring said shaft to its initial position, means operating when the shaft reaches its initial position to release the contact finger and the shaft so that said segment then falls against its stop, and governing mechanism on the train controlled by the cooperation of said contact segment and said contact finger.

30 13. Railway traffic controlling apparatus comprising means in the trackway for supplying impulses to trains, and train carried governing mechanism selectively responsive to the time interval between the beginning 35 of each impulse and the beginning of the next impulse.

14. Railway traffic controlling apparatus comprising means in the trackway for supplying impulses to trains, means controlled 40 by traffic conditions for varying the time interval between the beginning of each impulse and the beginning of the next impulse, and train carried governing mechanism selectively responsive to the time interval between the beginning of each impulse and the beginning of the next impulse.

15. In a continuous indication train control system, in combination, a translating device on the train, means controlled by traffic 45 conditions for transmitting electrical impulses through said translating device, mechanism controlled by said translating device operating through a certain phase and then returning to initial position continually so long as impulses are transmitted through said translating device, and indication means controlled by said mechanism and held at one indication so long as said mechanism completes its phase of operation in 50 predetermined intervals.

16. In a continuous indication train control system, in combination, a track, a vehicle travelling thereon, a translating device on the vehicle, means controlled by traffic 70 conditions for intermittently energizing said device, a timing device on the vehicle, a member under the joint control of said timing device and said translating device and caused thereby to operate through a pre-determined phase and then return to initial 75 position, and indication means controlled by said member and held at one indication only so long as said member completes its phase of operation in regularly recurring intervals.

80 17. In a train control system, in combination, a track, a vehicle travelling thereon, a member on the vehicle having an initial position, means for moving said member from initial position at a constant rate, impulse means controlled by traffic conditions for restoring said member to initial position, and indication means held at one indication only so long as the extent of movement of said member does not exceed or fall 90 short of a substantially constant value.

18. In a continuous indication train control system, in combination, a track, a vehicle travelling thereon, a translating device on the vehicle, means for energizing and 95 de-energizing said translating device continually and at regular intervals while the vehicle is travelling under clear conditions, a member on the vehicle driven at a constant speed, means controlled by said translating device for affecting the movement of said member upon the reception of each impulse, and indication means governed by said member.

100 19. In a continuous indication train control system, in combination, a track, a vehicle travelling thereon, a translating device on the vehicle, means for energizing and de-energizing said translating device continually and at regular intervals while the vehicle is travelling under clear conditions, a member on the vehicle having an initial position, continuously operating means for moving said member away from its initial 110 position at a constant speed, means controlled by said translating device for restoring said member to initial position upon each energization thereof, and indication means controlled by said member.

115 20. In a continuous indication train control system, in combination, a track, a vehicle travelling thereon, a translating device on the vehicle, means for energizing and de-energizing said translating device continually and at regular intervals while the vehicle is travelling under clear conditions, a member on the vehicle having an initial position, continuously operating means for moving said member away from its initial 120 position at a uniform rate, means controlled 125

by the translating device for restoring said member to initial position upon each energization thereof, a train control circuit, and means for closing said circuit when said translating device is energized only if said member is in a predetermined position.

21. In a continuous indication train control system, in combination, a track, a vehicle travelling thereon, a translating device on the vehicle, means controlled by traffic conditions for transmitting electrical impulses through said translating device at

regular intervals, a member on the vehicle moved to an initial position upon the reception of each impulse, means for moving said member away from initial position at a predetermined rate, a train control circuit, and means for closing said circuit upon the reception of each impulse provided said member has reached a predetermined position.

In testimony whereof I affix my signature.

HAROLD O. HOLTE.
